DOUBLE VERTICAL INTERLOCK BOTTLE
CRATE

Louis B. Tarter and William Tarter, New York,
N. Y., assignors, by mesne assignments, to Morris Goldman, Aldenville, Pa.

Application April 26, 1943, Serial No. 484,650

3 Claims. (Cl. 217—19)

This invention relates to crates for milk bottles and an object of this invention is to improve the construction of slatted crates to prevent breakage of the slats.

Crates for milk bottles and the like have heretofore been made with the rods which form the bottoms for the compartments of the crate running completely through the lower wooden slats of the crate. This put a strain on the lower slats and weakened the slats. The holes which support the rods in the lower slats wear, and the strain on the lower slats in supporting these rods weakens and breaks the slats and they must be replaced.

The breakage of the bottom slats is especially aggravated because of the necessity of drilling six or more holes through each end slat, and when a heavy blow is applied accidentally to a slat the slat breaks through where the holes have been drilled and the utility of the crate is thereby destroyed.

Crates having the walls thereof formed from a plurality of spaced slats have been so constructed heretofore that it has been difficult to replace the broken slats.

An object of this invention is to securely retain the bottle supporting grid at the bottom of the crate and to facilitate the installation of this bottle supporting grid.

Another object of this invention is to reinforce the opposite walls of a crate by extending the rods of the crate to be substantially co-extensive with the over-all dimensions of the crate, the rods extending between the slats of the superposed tiers and by interlocking the end portions of the rods with the opposite slats.

With the above and other objects in view, the invention will be hereinafter more particularly described, and the combination and arrangement of parts will be shown in the accompanying drawing and pointed out in the claims which form part of this specification.

Reference will now be had to the drawing, wherein like numerals of reference designate corresponding parts throughout the several views, in which:

Figure 1 is a perspective view of a bottle crate embodying this invention.

Figure 2 is a cross-sectional view, the section being taken as on line 2—2 in Figure 1.

In the illustrated embodiment of the invention, the numeral 10 indicates a sectional crate for milk bottles and the like, and comprising bottom, intermediate and upper sections or tiers 11, 12, and 13 made of wood slats.

The bottom section 11 is made of side slats 14 and end slats 15 secured in unitary relation in any suitable manner. The intermediate section is similarly made of side slats 16 and end slats 17. The upper section is made of side slats 18 and end slats 19.

A bottom grid 20 is made of steel rods or wires 21 and 22 integrally secured together in right-angular relation by spot welding. Each end portion of the wires 21 and 22 is bent in U-shape form, providing inner feet 23 and outer feet 24. The distance between the feet 23 is made so that the grid fits snugly into the bottom section 11.

As shown in Figure 2 the slats 14 and 15 are of rectangular cross-section and positioned with their larger sides vertically. The slats 14 and 15 have vertically drilled apertures 25 extending only a small distance down into the slats. The distance between the centers of the outer feet 24 is made to correspond with the distance between centers of the holes in opposite slats.

In assembled crate-forming relation, the U-shaped ends 26 rest on top of the end slats of the bottom section 11. The lower surface 27 of the grid 20 is positioned considerably below the top surface of the lowermost section 11 of the crate 10 and this grid terminates considerably above the bottom of the crate. When the grid 20 is placed in the lower section 11 the grid surface 27 provides a floor on which the bottles rest. The floor wires are arranged in closely spaced pairs.

The base portions of the U-shaped ends 26 of the wires 21 and 22 of the grid 20 extend horizontally between the lower and intermediate sections 11 and 12 and space the said sections apart sufficiently to form ventilating openings 28 between the said sections.

An upper grid 30 is made of steel wires 31 and 32 integrally secured together in right-angular relation by spot welding. Each end portion of the wires 31 and 32 is bent in L-shaped form, providing feet 33. The distance between the feet of the respective wires is made to correspond with the distance between centers of holes 34 in opposite slats. The wires 31 are sufficiently long to extend horizontally between the top and intermediate sections 13 and 12 and space the said sections apart sufficiently to form ventilating openings 35 between the said sections. The wires 32 are bent slightly upwardly at the spot weld 36 points 36 and extend horizontally between the top and intermediate sections and also space said sections apart.

A spacing frame 40 made of right-angularly positioned and suitably interconnected wires 41 and 42 form rectangular pockets between them for bottles. The ends of the wires 41 and 42 are L-shaped and form feet that are positioned in right-angular relation with the frame 40, and similar to the feet 33 in the grid 30. The L-shaped foot ends of the wires 41 and 42 are also received in vertical apertures (not shown) in the upper portions of the slats of the bottom section 11. The pockets in the spacing frame 40 are of the same size and are positioned in vertical aline-

ment with rectangular pockets 43 for bottles in the top grid 30.

For the purpose of uniting the several superposed sections 11, 12, 13 into a unitary structure, we employ angle irons or corner irons 45 which are secured to the four corners of the crate by rivets 46 passing through the wood slats.

It will thus be seen that the crate 10 is built up of three independent slatted sections 11, 12, 13, and three grid-shaped skeleton frames 20, 30, 40. It is to be noted that where presently, when conveyor dogs apply forcible blows to the bottom slats of the crate, the bottom slats get broken, that in the structure herewith disclosed, in addition to the mechanically interlocked and anchored relation of the outer feet 24 of the bottom grid 20 with the slatted bottom section 11, that the inner feet 23 of the U-shaped ends of the respective cross wires provide wire abutments against which the slats react when a blow is applied to the crate from the exterior and that these abutments provide additional reinforcement to the slats of the bottom section, preventing the bottom slats from inward movement or distortion.

The mechanically interlocked relation of parts also prevents distortion or warpage of the wooden slats when in contact with ice or water.

The importance of providing vertically drilled holes in the upper portions of the slats instead of horizontally drilled holes in the lower portions of the slats arises from the fact that the wooden slats are weaker in tension than in compression. In accordance with proper design, holes should not be drilled in the lower portions of the slats, so that the lower portions are bodily intact and therefore adapted to resist maximum tensile stresses.

In order not to weaken the lower portions of the slats we drill holes vertically in the upper portions of the slats, that is, in the compression zone.

In accordance with the patent statutes we have described and illustrated the preferred embodiment of our invention, but it will be understood that various changes and modifications can be made therein without departing from the spirit of the invention as defined by the appended claims.

We claim:

1. In a bottle crate having bottom intermediate and top sections made of slats, said bottom and intermediate slats having vertically positioned wire receiving apertures extending downwardly from their upper surfaces and terminating in the upper portions of said slats, a bottom grid adapted for supporting bottles, said bottom grid being supported between said bottom and intermediate sections with its supporting surface positioned below the upper level of said bottom section, said bottom grid having U-shaped lateral extensions providing end portions in interlocking engagement with said vertical apertures in said bottom slats, portions of said U-shaped extensions being in contacting relation with the vertical inner surfaces of said bottom slats and providing abutments for said bottom slats, a bottle spacing frame supported between said bottom and intermediate sections and lying in a horizontal plane on the upper surfaces of said bottom section, said bottle spacing frame having L-shaped lateral extensions in interlocking engagement with vertical apertures in the upper portions of said bottom slats, and a bottle spacing grid mounted between said upper and intermediate sections and having lateral ex-

tensions in interlocking engagement with vertical apertures in the upper portions of said intermediate slats, said grids serving to maintain said crate sections in spaced-apart relation and providing 5 openings for ventilation between said sections, and corner angle members uniting said sections in unitary relation.

2. In a bottle crate having side and end walls made of slats and forming bottom intermediate 10 and top sections, said bottom and intermediate slats having vertically positioned wire receiving apertures extending downwardly from their upper surfaces and terminating in the upper portions of said slats, a bottom grid adapted for supporting 15 bottles, said bottom grid being supported between said bottom and intermediate sections with its supporting surface positioned below the upper level of said bottom section, said bottom grid having U-shaped lateral extensions providing end portions in interlocking engagement with said vertical apertures in said bottom slats, portions of said U-shaped extensions being in contacting relation with the vertical inner surfaces of said bottom slats and providing abutments for said 20 bottom slats, a bottle spacing frame supported between said bottom and intermediate sections and lying in a horizontal plane on the upper surfaces of said bottom section, said bottle spacing frame having L-shaped lateral extensions in interlocking engagement with vertical apertures in the upper portions of said bottom slats, and a bottle spacing grid mounted between said upper and intermediate sections and having lateral extensions in interlocking engagement with vertical apertures in the upper portions of said intermediate slats, said grids being formed of right angularly 25 extending rods passing over one another in contacting relation, said rods being united in permanent intimate union by welding at their contact points whereby said rods are held together in non-slidable relation to each other, said grids serving to maintain said crate sections in spaced-apart relation and providing openings for ventilation between said sections, and corner angle members uniting said sections in unitary relation.

3. In a bottle crate having bottom intermediate and top sections made of slats, said bottom and intermediate slats having vertically positioned wire receiving apertures extending downwardly from their upper surfaces and terminating in the upper portions of said slats, a bottom grid adapted for supporting bottles and a bottle spacing frame supported between said bottom and intermediate sections and lying in a horizontal plane on the upper surfaces of said bottom section, said bottom grid having its supporting surface positioned below the upper level of said bottom section, a bottle spacing grid mounted between said upper and intermediate sections, said grids and frame having lateral extensions in interlocking engagement with said vertical apertures in said slats, said grids and frame being formed of right angularly extending rods passing over one another in contacting relation, said rods being united in permanent intimate union by welding at their contact points, whereby said rods are held together in non-slidable relation to each other, said grids serving to maintain said crate sections in spaced-apart relation and providing openings for ventilation between said sections, and corner angle members uniting said sections in unitary relation.
